UNITED STATES PATENT OFFICE

103,393

DESIGN FOR A PRINT DEVICE FOR DAIRY PRODUCTS

Charles Doering, Chicago, Ill.

Application December 21, 1935, Serial No. 60,221

Term of patent 14 years

To all whom it may concern:

Be it known that I, Charles Doering, a citizen of the United States and a resident of Chicago, county of Cook, and State of Illinois, have invented a new, original, and ornamental Design for a Print Device for Dairy Products, of which the following is a specification, reference being had to the accompanying drawing, forming part thereof.

In the drawing:

The figure is a perspective view of a print device for dairy products showing my new design.

The dominant feature of my design resides in the configuration of the frame.

I claim:

The ornamental design for a print device for dairy products substantially as shown and described.

CHARLES DOERING.
